MANUFACTURE OF AIR FILTERS

Armand Jacques Julien Poelman, Paris, France;
vested in the Alien Property CustodianApplication June 3, 1941, Serial No. 396,457
In France January 11, 1939

5 Claims. (Cl. 93—1)

It is known to make an air-filter from a strip of paper by folding it uniformly into zigzag shape, then joining its ends in order to form a sort of cockade with radial folding lines. The periphery of this cockade is preferably given the general shape of a truncated cone by cutting slantingly the corresponding edge of the paper after effected folding.

A method is also known for fixing such a filter by its periphery to a mounting of a corresponding shape, by means of a lute such as asphaltum. According to this method, the said mounting is rotated about an inclined axis passing through its centre, the lute is poured in liquid state into the mounting, in which it spreads out under the combined effect of the rotation and inclined position given to the mounting, whereupon, without stopping the rotation of the mounting and rotating the filter with the same speed, the latter is placed in position in the mounting.

The object of the present invention is to provide a machine for realising this method conveniently and with a high capacity of production.

Another object of the invention is to provide, in a machine of the type indicated, means for ejecting the filters when they have been fixed on their mounting.

The invention further has the object of providing means for pouring the required amount of molten lute exactly in the required place of the mounting.

Other objects of the invention will appear from the following specification of an embodiment of the invention with reference to the joined drawings, in which:

Figure 1 is a lateral elevation of the machine.

Figure 2 is a corresponding plan view.

Figure 3 is a partial section at an enlarged scale, along the line III—III of Figure 1.

Figure 4 is a similar section, at the same scale, along IV—IV of Figure 1.

Figure 5 is a perspective view showing the form of a filter.

Figure 6 shows similarly the folded strip used for making the filter.

Figure 7 shows the mounting in a section through the axis, and

Figure 8 shows the filter, also in axial section.

The filter to be luted on a mounting is formed from a strip of paper, folded transversely into uniform zigzags (Figure 6). One edge *c* of this strip is cut in a slope with respect to the direction of the folding edges *a*. The other edge *b* is left perpendicular to said direction. The strip is closed on itself by assembling both its ends. It

then forms the radially folded cockade with a central circular hole shown on Figure 5.

For making the drawings clearer, only a small number of folds have been shown, but in practice their number is much greater and they are much closer to one another in order to give the filter the maximum useful surface with respect to its shape.

Due to the inclination of edge *c*, the filter periphery has the general shape of a truncated cone. The mounting A (Figure 7) consists in a cup of corresponding truncated cone shape, in any suitable substance, for instance a thin metal. Its flat bottom is apertured. Its edge *f* is folded outwardly in a plane parallel to that of the bottom part. The central aperture of the filter is closed by two small covers *a*, *e* fixed with a lute (Figure 8).

The filter is fixed upon its mounting by means of the machine shown in Figures 1 to 4.

The machine frame 1 is pivoted at 10 to a base plate 2 so that its inclination may be varied at will. It is maintained in the required inclined position by means of the bar 11 pivoted at 20 to the base plate. This bar forms a slide traversed by a pin screwed into the frame 1 and fitted with a locking nut 12.

The frame 1 carries a fixed head and a movable head mounted in a line on the same axis.

The first head consists of two bearings 13, 14 carrying a hollow shaft 3. On this shaft is keyed, between the two bearings, a grooved pulley 30. At the upper end of the shaft is keyed a box 31 adapted to receive the filter mountings.

The movable head comprises a fixed support 15 in which is slidably mounted a hollow cylindrical member 4. This member carries a radial pin 40 passing through a longitudinal mortise 16 provided in the wall of support 15. The pin engages a lever 5 pivoted at 50 to the foot of support 15. By acting upon this lever, it is thus possible to move longitudinally the member 4. The lower part of this member is connected, over a ball bearing 41 (Figures 4), to one end of a hollow

45 shaft 6. On the latter is mounted a driving box 7 slideable on the shaft under the control of spring 10. Inside box 7, the hollow shaft 6 is ended by an elastic mandrel 60 adapted for carrying the filter and surrounded concentrically by a plate 61. The edge of box 7, largely cut out, forms a rib 11 (Figure 4) corresponding to another rib 32 provided on the edge of box 31 of the fixed head.

The frame 1 forms a wing 16 (Figure 2) on which is fixed an electric motor 8 driving over a belt the grooved pulley 30 of the fixed head.

Through the central bore of shaft 3 of the fixed head passes a sliding rod 9. As shown in Figure 3, this rod is fixed to the centre of a movable plate 90 of box 31. Around the edge of this box are arranged a number of slots 33, through each of which a spring blade 34, fixed outside the box, protrudes inside the latter.

Into the central bore of member 4 and of shaft 6 (Figure 4) penetrates a second sliding rod 42 reaching to the centre of the filter-carrying mandrel 60.

The lute used is maintained molten by any suitable means, in a vessel 100, the bottom of which is provided with a central pouring aperture controlled by a tappet 101 actuated by a spring. Said vessel is supported by the vertical rod 102 fixed to the base plate 2. The horizontal end 103 of the lute container engages the bore of a head 104 provided with a locking spring and further traversed by the vertical rod 102. Due to this arrangement, the vessel 100 may be set at any required level and in any suitable position. The top of the tappet 101 is pivoted to a horizontal lever 105 pivoted to the support 106. To the other end of this lever is pivoted a slide 107 which, when actuated, permits the lute to flow out.

To lever 105 is also pivoted a small bar 108 which, through the means of a bent pivoted lever 109, actuates the pivoting link 110. The latter carries a cup-shaped member 111 which, when the tappet 101 is in the open position, is thus held clear from the stream of molten lute running out of vessel 100. It is, on the contrary, brought back below the outflow aperture of the vessel when the tappet 101 closes the latter.

This machine operates as follows:

The frame 1 is set at the required slope and the vessel 100 containing the molten lute is brought to a position in which its pouring hole lies on the axis of the heads, above the lower edge of box 31. The motor is then started and the box 31 fitted with a mounting A (Figure 7), the folded edge *f* of which is applied to that of the box and which is mounted in the latter by the blade springs 34.

A filter B (Figure 5) is placed on the mandrel 60 which is engaged in one of the covers *d* closing the central aperture of the filter.

The mounting is then filled with the required amount of molten lute which spreads over the inner conical surface of the mounting under the combined effect of its inclined position and rotation. After stopping the flow of molten lute, the lever 5 is actuated, bringing first to mesh the box 31 with box 7 which is thus also driven in rotation with shaft 3 and the mounting, together with the filter. At the end of its stroke, lever 5 rocks shaft 6 with respect to the box 7 against the action of spring 70. The filter is pushed in its mounting and its edges are thus sealed in the lute.

By exerting a push on the plate 90 by means of rod 9, the mounting fitted with its filter is ejected from box 31 while the box 7 is brought

back to its initial position, together with the mounted filter which remains engaged on the mandrel 60. A push on rod 42 suffices for finally ejecting the mounted filter. Since the mounting may still be warm, one may provide, for receiving this part, a small flanged plate with a handle.

What I claim is:

1. Machine of the type described, particularly adapted for fixing a filter to a mounting and comprising, in combination, a frame, a base plate pivoted to this frame and inclined by an adjustable angle with respect to the horizontal, on this base plate two supports arranged at different heights, a mounting carrying member adapted to receive said mounting and mounted rotatably on the support mounted below the other one on said base plate, a filter carrying member adapted to receive the filter to be fixed and rotatably and slidably mounted on the second support arranged above the other one on said inclined base plate, means for rotating said mounting carrying member, means for moving said filter carrying member and said mounting carrying member towards one another for bringing the filter into contact with the mounting, means for rotatably coupling said filter carrying member with said mounting carrying member before bringing the filter into contact with the mounting, means for supplying said mounting carrying member with an amount of lute necessary for sealing said filter to said mounting.

2. Machine according to claim 1, in which said filter carrying member is constituted by a hollow shaft carrying at its inner end a mandrel receiving the filter, said means for moving the filter carrying member towards the mounting carrying member comprising a member sliding on said second support and a control member for actuating said sliding member.

3. Machine according to claim 1, in which said means for coupling in rotation said filter carrying member with said mounting carrying member comprise a member in form of a cylindrical box coupled in rotation with said filter carrying member and slidable with respect to the latter in order to permit this filter carrying member to continue its movement towards the mounting carrying member with the view of bringing the filter into contact with the mounting.

4. Machine according to claim 1, comprising further, means for bringing back, after sealing the filter to its mounting, said filter carrying member provided with the sealed filter, to its initial position, and means for ejecting from the filter carrying member out of the machine the filter sealed to its mounting.

5. Machine according to claim 1, in which said means for supplying lute to said mounting carrying member comprise a lute containing tank mounted adjustably in height and position above said mounting carrying member, and a device controlling the distribution of lute by said tank.

ARMAND JACQUES JULIEN POELMAN.
